UNITED STATES PATENT OFFICE.

FREDERICK A. HART, OF JERSEY CITY, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,215,370.

Specification of Letters Patent. Patented Feb. 13, 1917.

Application filed August 9, 1911, Serial No. 643,109. Renewed January 29, 1916. Serial No. 75,170.

To all whom it may concern:

Be it known that I, FREDERICK A. HART, a citizen of the United States, residing in Jersey City, in the county of Hudson and State of New Jersey, have invented certain new and useful Improvements in Type-Writing Machines, of which the following is a specification.

This invention relates to carriage-return devices employed in certain classes of machines, for instance in combined typewriting and computing machines of the class illustrated in my pending applications No. 466,836, filed December 10, 1908, and No. 15 596,451, filed Dec. 9, 1910.

According to said first-mentioned application, in performing the operation of addition upon a typewriting machine, the numeral keys not only print upon the work sheet, but also set up certain pins, and after the completion of the writing of a number, a handle (designated herein as 16) is pulled for the purpose of turning certain dial wheels each to an extent determined by the 25 key-set pin associated therewith. Said handle is used for reciprocating a general operator, which in turn operates said dial wheels.

Another function performed by said general operator, which may be driven by a motor as well as by hand as in my application, No. 596,451, above mentioned, is to return the carriage of the typewriter. In practice, the length of run of the typewriter carriage varies, whereas the stroke of the general operator is uniform. Hence in said applications, there was shown an adjustment device between said general operator and the typewriter carriage, so that during 40 part of the advance stroke of the general operator the typewriter carriage could remain stationary, if desired; the general operator picking up the carriage at the proper time, so that the carriage would be driven during 45 only the desired portion of the stroke of the general operator.

The length of stroke of the typewriter carriage is usually determined by means of a margin gage, which is placed at the right hand portion of the typewriting machine and regulates the width of the left hand margin on the work sheet.

In said applications, it was necessary not only to adjust the relation between said gen-

eral operator and the carriage, but also to 55 adjust the aforesaid margin gage, and unless the operator was particular to effect both adjustments in the proper manner, difficulty might result, since the carriage might be arrested by its margin gage prior to the completion of the forward stroke of the general operator; or the adjustment between the general operator and the carriage might not correspond with the adjustment of the margin gage on the typewriter.

One of the principal objects of the present improvements is to avoid this difficulty and to render the device more simple in construction and operation.

To these and other ends, I connect to the 70 margin gage of the typewriter a device which also sets the aforesaid adjustment mechanism between the general operator and the carriage. It is therefore only necessary for the operator to adjust the margin 75 gage in the usual manner, whereupon the carriage, during its return strokes, will always stop at the point determined by said margin gage, and the proper connection is always made between the aforesaid general 80 operator and the carriage, so that the general operator imparts to the carriage the proper amount of movement, and there is no danger of faulty action of any of the parts.

In other words, the invention relates 85 largely to an automatic adjustment of the carriage return mechanism. The invention, however, is not limited to use on computing machines, as certain features thereof are adapted to carriage-returning mechanism, 90 whether used in connection with computing mechanism or not.

In said applications the return of the carriage was effected by manipulation of a device remote from the carriage itself, and the 95 carriage was returned either manually or automatically, concomitantly with the actuation of certain other mechanism; and one of the features of the present invention resides in providing means to adjust the connection between the carriage and a carriage-returning device having uniform movement, to correspond to the variable movement of the carriage. The device for limiting the return of the carriage is adjusted 100 conveniently with the device which connects the carriage to its returning mechanism. This feature of the invention may be carried out 105

in a variety of ways, as for example, by providing a stop or margin gage for the return movement of the carriage, which is operatively connected to a device which governs the extent to which the carriage returning device moves the carriage.

Other objects and advantages will herein-after appear.

In the accompanying drawings,

10 Figure 1 is a side view in elevation, showing the invention as applied to an Underwood typewriter, parts being omitted to avoid confusion.

15 Fig. 2 is a front view in elevation, showing the return carriage stop at one position of adjustment.

Fig. 3 is a view similar to Fig. 2, showing the return carriage stop and the connected mechanism at another point of adjustment.

20 Fig. 4 is a vertical section taken along the operator shaft.

Fig. 5 is an enlarged fragmentary view in side elevation, with parts broken away to show the under-lying structure, and 25 showing the control in a position corresponding to the position of the stop, as illustrated in Fig. 2.

Fig. 6 is a view similar to Fig. 5, showing the control in the position corresponding 30 to the position of the stop, as illustrated in Fig. 3.

Fig. 7 is a horizontal sectional view.

Fig. 8 is a fragmentary detail perspective view of certain of the coöperating stops.

35 Showing the invention as embodied in an Underwood typewriter, 1 indicates a carriage which supports the usual platen 2 in the customary manner. The carriage 1 is mounted in the usual way to slide back and 40 forth on a frame 3, for the purpose of bringing the work sheet to the different positions desired in the actuation of the machine.

45 It is generally understood that the carriage 1 travels from right to left, as viewed in Figs. 2 and 3, in the ordinary operation of the typewriter in letter-spacing. It has been found desirable to limit the extent of movement of the carriage in both directions, so as to limit the width of the type-writing on the work sheet supported by the platen 2. For this purpose, the carriage 1 is provided with a margin stop or gage 4, which engages at the end of its movement in a letter-spacing direction, a stop 5, 50 adjustably mounted on the frame 3 in any suitable manner, as by being slidingly supported on bars 6 and 6' and adapted to be secured in any adjusted position by a lock 7, which may be in the form of a ratchet pawl, engaging a rack on bar 6'.

55 The return movement of the carriage after the writing of a line, may be also limited in a similar manner by the carriage stop 4 engaging a margin stop or gage 8, which simi-

lar to the stop 5, is slidingly mounted on bars 6 and 6' and adapted to be secured in any adjusted position by means of a lock 9, which is shown in the form of a pawl engaging a rack on the bar 6'.

70 In order that the operative may accurately adjust the limits of throw of the carriage, a scale 10 may be provided in such a position, that the stops 4, 5 and 8 will be conveniently located with respect thereto, so 75 that the relative positions of the stops 5 and 8 can be easily read on the scale. In order to aid the facility of reading, these stops may be provided with pointers 11, 12 and 13 which overlap the scale 10.

80 While the stop 4 on the carriage may be a simple projecting lug, it may also be of the type shown in Fig. 8 which is common to the Underwood typewriters and embodies a cam lug 4^a, which coöperates with the 85 stop 5, and a spring-pressed pivotally mounted releasable lock 4^b, which coöperates with a lug 8^a forming part of the stop 8.

85 As is usual in the Underwood machine, there is provided a platen spacer 14 which 90 may be seized by the operative in the operation of returning the carriage, and it will simultaneously revolve the platen the desired amount, to bring a fresh portion of the work sheet in operative position.

95 As described in my above-mentioned application, the return of the carriage and the operation of the platen spacer may be controlled from a point other than the carriage itself, as for example by connecting to the 100 spacer 14, a flexible connection 15 shown in the form of a ribbon, and adapted to be operatively connected to an operator 16 through intermediary mechanism. The operator 16 may be of any suitable type, such 105 as automatic or power-actuated, as shown in my above-mentioned applications, or it may be a manual means, as the hand-crank here shown.

110 In the embodiment of the invention here-with illustrated, the ribbon 15 passes over a guiding roller 17 intermediate its ends, so as to change its direction of pull, and is connected at the opposite end from that at which it is attached to the spacer 14, to a 115 drum 18. The drum 18 is secured to a stub-shaft 19, on which is also secured a pinion 20 meshing with a gear 21 loosely mounted on a shaft 22. In this case, the operator 16 is shown as being loosely mounted on the 120 shaft 22, and connected to an arm 23, as by means of a pin 24, so as to move with the arm 23, and also with the shaft 22 to which the arm 23 is fixedly secured.

125 The arm 23 is provided with a pinion 25 which meshes with the gear 21 in such a manner, that the arm 23 and thus the operator 16, are free to rotate relative to the gear 21 until the pinion 25 meshes with a corresponding pinion 26 also meshing with 130

the gear 21, and carried by a control 27, shown in the form of an arm loosely mounted relative to the shaft 22, as by being journaled on the hub extensions of the gear 21.

5 It will be seen that when the gear 25 meshes with the gear 26, the operator 16 will be locked to the gear 21, whereby this mechanism forms a clutch connecting the operator to the gear 21, so that the former

10 will be capable of driving the latter.

It is to be noted that the initial position of the control 27 governs the amount of ineffective or inactive movement of the operator 16 before the pinion 25 locks with the 15 pinion 26 to form a driving connection between the operator and the gear 21. It is desirable to effect the positioning of the control 27 from an accessible point, and also as stated above, in connection with the adjustment of the limit stop for the return of the 20 carriage.

In the embodiment of the invention shown herewith, the control 27 has operatively connected thereto in a suitable manner, as for 25 example, by being rigidly secured thereto, an actuator 28, shown in the form of a bell crank lever having a segment rack 29 formed on one arm thereof, which meshes with a pinion 30 secured in driving relation with 30 a drum 31.

The drum 31 provides means on which a flexible connection 32, shown in the form of a band, can be wound, and this flexible connection extends through suitable guiding 35 means shown in this case in the form of an opening 33 in the frame 3, to a point where it is suitably secured to the carriage return stop 8. While the movement of the stop 8 to the left will actuate the control in one 40 direction, it is desirable to actuate it in the opposite direction, and for this purpose the other arm of the actuator or bell-crank lever 28 is connected to a spring 34, which is fixedly secured at its opposite end.

45 It will thus be seen that as the stop 8 is adjusted and locked in its adjusted position to vary the return limit of the carriage 1, the flexible connection 32 will be taken up or let out a corresponding amount which will be 50 allowed for by the turning of the drum 31 under the restraining control of the spring 34. This will vary the position of the control 27 relative to the initial position of the arm 23, and thus the operator 16, so that 55 the latter will have a variable ineffective travel which will allow for the difference in its definite fixed travel, and the variable throw of the carriage 1. For example, if the stop 8 be moved from the position shown 60 in Fig. 2 to the position shown in Fig. 3, the return movement of the carriage will be limited to the position which the carriage occupies in Fig. 3, where as before, it was limited to the position occupied in Fig. 2.

65 Inasmuch as the stop 8 limits the return of

the carriage by engagement with the stop 4 on the carriage, the operating return mechanism for the carriage must be correspondingly limited. This is done as will evidently be seen, by the flexible connection 32 unwinding on the drum 31, thus swinging the control arm 27 from the position occupied in Fig. 5 to the position occupied in Fig. 6, whereby the arm 23 and thus the operator 16, will have a greater inactive or 70 ineffective throw before the pinions 25 and 26 mesh to lock the operator in driving relation with the gear 21.

Since the operator 16 is locked to the gear 21, it will rotate the drum 18 through 80 the intermediary of the gear 20, and thus wind up on the flexible connection 15, and return the carriage 1, at the same time actuating the spacer 14 and spacing the platen, during the remainder of the movement of 85 the operator.

The operator itself may be returned to its initial position through any suitable mechanism connected or not to the shaft 22, such as that indicated in my above-mentioned 90 applications, it being readily seen that the pinion 25 will disengage itself from the pinion 26, and travel to the right without disturbing the position of the gear 21, and thus without disturbing the position of the 95 carriage; that is to say, the upper end can have a free or ineffective return motion for its entire stroke or swing.

As the carriage itself moves toward the left in Figs. 2 and 3, under the actuation 100 of the usual letter-spacing or column-spacing mechanism, the flexible connection 15 will gradually unwind from the drum 18 rotating the same, and thus returning the gear 21 and the control 27 to their initial position 105 reached at the arrival of the carriage 1 at its limit of travel toward the left, determined by the carriage stop 5.

It will be noted that the stop or gage 8 might be used merely as an indicator and 110 not positively engage and obstruct the movement of the carriage. In such an event, the extent of effective movement of the operator would be depended upon to determine the limit of return movement of the carriage. It is, however, preferred to use the member 8 as a stop, as well as an indicator, inasmuch as the limit of movement of the carriage would probably be more accurately 115 determined.

Variations may be resorted to within the scope of the invention, and portions of the improvements may be used without others.

Having thus described my invention, I claim:

1. The combination with a typewriter carriage, of an operator for manipulating said carriage, a stop for limiting the travel of said carriage, and controlling means adjusted by said stop for governing the effec- 120

- 5 tive movement of said operator to correspond to the extent of travel of said carriage determined by said stop.
- 6 2. The combination with a typewriter carriage, of an operator for manipulating said carriage, a stop for limiting the travel of said carriage, and controlling means adjusted by said stop for governing the effective movement of said operator to correspond to the extent of travel of said carriage determined by said stop; said stop being located in a readily accessible position in front of said carriage.
- 7 3. The combination with a carriage, of a stop for limiting the travel of said carriage, an operator for traversing said carriage, a control for governing the extent of movement of said carriage by said operator, and connections between said stop and said control, whereby the action of the latter is governed from the former.
- 8 4. The combination with a carriage, a scale arranged in juxtaposition to said carriage, a margin-regulating device mounted to move along said scale to determine the extent of travel of said carriage, an operator for traversing said carriage, and operative connections between said margin regulating device and said operator, whereby the effective movement of the latter is determined by the position of the former.
- 9 5. The combination with a carriage, of a stop for limiting the movement of said carriage, means for traversing said carriage, an operator for actuating said means, a mechanism for connecting said operator to said means for a portion of the movement of said operator, and connections between said mechanism and said stop whereby said stop determines the extent of effective movement of said operator.
- 10 6. The combination with a carriage, of an operator for traversing said carriage, a control for governing the extent of movement of said carriage by said operator, a stop for limiting the movement of said carriage, connections between said stop and said control for adjusting the position of said control, and thereby varying the extent of movement of said carriage by said operator, and spring means for modifying the movement of said control.
- 11 7. The combination with a carriage, of means for traversing said carriage, an operator for manipulating said means, clutching mechanism for connecting said operator to said means, said clutching mechanism being disconnected for a portion of the movement of said operator, a stop for limiting the travel of said carriage, and operative connections between said stop and said clutching mechanism whereby the period of connection of said operator with said means through said clutching mechanism may be regulated.
- 12 8. The combination with a carriage, of an operator for traversing said carriage, connections between said operator and said carriage whereby the movement of the former may be transmitted to the latter, a stop, a flexible connection secured to said stop, a drum for winding said flexible connection, and an actuator operated by said drum for controlling the connection between said operator and said carriage to determine the extent of movement of said carriage by said operator.
- 13 9. The combination with a carriage, of an operator for traversing said carriage, a control for regulating the movement of said carriage by said operator, a stop for limiting the movement of said carriage, an actuator for said control, a drum adapted to operate said actuator, and a flexible connection wound on said drum and connected to said stop whereby said actuator and said control may be governed from said stop.
- 14 10. The combination with a carriage, of an operator for traversing said carriage, a control for governing the extent of movement of said carriage by said operator, a bell crank lever connected to said control and having a segment rack thereon, a gear meshing with said rack, a drum connected to said gear, a flexible connection wound on said drum, and a stop connected to said flexible connection for concomitantly limiting the travel of said carriage and regulating the adjustment of said control.
- 15 11. The combination with a carriage, of an operator for traversing said carriage, a control for governing the extent of movement of said carriage by said operator, a bell crank lever connected to said control and having a segment rack thereon, a gear meshing with said rack, a drum connected to said gear, a flexible connection wound on said drum, a stop connected to said flexible connection for concomitantly limiting the travel of said carriage and regulating the adjustment of said control, and a spring coöperating with said stop to vary the position of said control.
- 16 12. The combination with a carriage, of a drum, a flexible connection wound on said drum and connected to said carriage, whereby the movement of the one will be transmitted to the other, a pinion connected to said drum, a loosely mounted gear drivingly connected with said pinion, an operator, a pinion meshing with said gear and connected to said operator, a control for governing the driving connection of said operator with said gear, said gear control including an arm having a pinion thereon meshing with said gear, and adapted to mesh with said pinion connected to said operator to lock said operator to said gear, a stop, and a connection between said stop and said arm for varying the position of said arm relative to said carriage.

- said gear, whereby the extent of movement of said carriage by said operator will be varied.
13. The combination with a carriage, of a drum, a flexible connection wound on said drum and connected to said carriage, whereby the movement of the one will be transmitted to the other, a pinion connected to said drum, a loosely mounted gear drivingly connected with said pinion, an operator, a pinion meshing with said gear and connected to said operator, a control for governing the driving connection of said operator with said gear, said gear control including an arm having a pinion thereon meshing with said gear, and adapted to mesh with said pinion connected to said operator to lock said operator to said gear, an actuator connected to said control and adapted to operate the same, a drum for operating said actuator, a stop for limiting the motion of said carriage, and a flexible connection connected to said stop and adapted to be wound on said last-mentioned drum.
14. The combination with a carriage, of a drum, a flexible connection wound on said drum and connected to said carriage, whereby the movement of the one will be transmitted to the other, a pinion connected to said drum, a loosely mounted gear drivingly connected with said pinion, an operator, a pinion meshing with said gear and connected to said operator, a control for governing the driving connection of said operator with said gear, said gear control including an arm having a pinion thereon meshing with said gear, and adapted to mesh with said pinion connected to said operator to lock said operator to said gear, a bell crank lever connected to said control and having a segment rack formed on one end thereof, a drum, a stop for limiting the movement of said carriage, a flexible connection connected to said stop and wound on said drum, and a gear meshing with said segment rack and secured to said last-mentioned drum, whereby the movement of said stop will vary the position of said control.
15. The combination with a carriage, of a drum, a flexible connection wound on said drum and connected to said carriage, whereby the movement of the one will be transmitted to the other, a pinion connected to said drum, a loosely mounted gear drivingly connected with said pinion, an operator, a pinion meshing with said gear and connected to said operator, a control for governing the driving connection of said operator with said gear, said gear control including an arm having a pinion thereon meshing with said gear, and adapted to mesh with said pinion connected to said operator to lock said operator to said gear, a bell crank lever connected to said control and having a segment rack formed on one end thereof, a drum, a
- stop for limiting the movement of said carriage, a flexible connection connected to said stop and wound on said drum, a gear meshing with said segment rack and secured to said last-mentioned drum, whereby the movement of said stop will vary the position of said control, and a spring connected to said bell crank lever for varying the position of said control.
16. The combination with a carriage, of an operator for traversing said carriage, a control for regulating the movement of said carriage by said operator, a stop for limiting the movement of said carriage, and connections between said stop and said control whereby said stop and said control may move concomitantly to regulate concomitantly the movement of said carriage directly by said stop and indirectly through said control.
17. The combination with a carriage, of an operator for traversing said carriage, said carriage having a variable length of travel, and said operator having a definite magnitude of movement, an adjustable control for varying the effective movement of said carriage by said operator, and means for fixing the adjusted position of said control.
18. The combination with a carriage, of an operator for traversing said carriage, said carriage having a variable length of travel, and said operator having a definite magnitude of movement, an adjustable control for varying the effective movement of said carriage by said operator, a stop for limiting the movement of said carriage, operative connections between said stop and said control whereby the position of the latter can be controlled from the former, and a lock for securing said control in a definite position of adjustment by fixing the position of said stop.
19. The combination with a carriage, of operating means for traversing said carriage, means for directly controlling the extent of movement of said carriage by obstructing the movement thereof, and means for indirectly controlling the movement of said carriage, through said last-mentioned means by controlling the effective manipulation of said carriage by said operating means.
20. The combination with a carriage, of operating means for traversing said carriage, a control for regulating the effective manipulation of said carriage by said operating means, and means for adjusting said control from a distant point to vary the travel of said carriage.
21. The combination with a carriage, of operating means for traversing said carriage, a control for regulating the effective manipulation of said carriage by said operating means, means for adjusting said control from a distant point to vary the travel of said carriage.

- trol from a distant point to vary the travel of said carriage, and a lock located at said distant point for fixing the position of adjustment of said control.
- 5 22. The combination with a carriage having a variable traveling movement, of a margin gage for said carriage, an operator for traversing said carriage, driving connections enabling the traversing of said carriage by said operator, and controlling means controlled from said margin gage for governing the effective period of said driving connections. 70
- 15 23. The combination with a traveling carriage having a variable movement, of a margin gage for said carriage, driving means for traversing said carriage, said driving means having variable passive and effective periods of action, and controlling means controlled from said margin gage for determining the effective periods of said driving means. 80
- 20 24. The combination with a traveling carriage having variable extents of movement to vary the extent of a typewritten line, of a margin gage for said carriage, an operator for traversing said carriage, said operator acting during a single movement, passively for a portion of its movement and effectively for the remainder of its movement, and controlling means controlled from said margin gage for determining the relative magnitude of the passive and effective movements of said operator. 85
- 25 25. The combination with a typewriter frame, of a typewriter carriage mounted to travel in said frame, a driving train for said carriage, a scale for said carriage, means on said train for automatically governing said driving train, and means at said scale for variably setting said governing means. 90
- 40 26. The combination with a traveling carriage and a scale therefor, of driving means for traversing said carriage along said scale and adapted to pick up said carriage at any position, and adjustable controlling means for said driving means having means to indicate on said scale the limit of movement of said carriage by said driving means. 95
- 50 27. The combination with a frame, of a carriage mounted to travel on said frame, a scale on said frame for said carriage, driving means for traversing said carriage along said scale and adapted to pick up said carriage at any position, said means located down off to one side of said frame, and adjustable controlling means for said driving means located at the top of the front of said frame adjacent to said carriage and said scale. 100
- 60 28. The combination with a frame, of a carriage mounted to travel on said frame, a scale on said frame for said carriage, driving means for traversing said carriage along 105
- 65 said scale and adapted to pick up said carriage at any position, said means located down off to one side of said frame, and adjustable controlling means for said driving means located at the top of the front of said frame adjacent to said carriage and said scale. 110
- 70 29. The combination with a traveling carriage having a variable traveling movement, and a scale therefor, of traversing means for driving said carriage along said scale and adapted to pick up said carriage at any position, and adjustable means for controlling the limit of a written line, connected to control the drive of said carriage by said traversing means. 115
- 75 30. The combination with a driving member having a uniform stroke, of a carriage, a scale for said carriage, and means at said scale and settable therealong for varying the effective stroke of said member on said carriage. 120
- 80 31. The combination with a driving member having a uniform stroke, of a carriage, a scale for said carriage, and means at said scale and settable therealong for varying the point at which said member shall begin to move idly. 125
- 85 32. The combination with a driving member having a considerable movement, and a carriage having a less movement, of a scale for said carriage, and means at said scale and settable therealong for varying the effective stroke of said member on said carriage. 130
- 90 33. The combination with a driving member having a considerable movement, and a carriage having a less movement, of a scale for said carriage, and means at said scale and settable therealong for varying the point at which said member shall begin to move idly. 135
- 95 34. The combination with a traveling carriage having a variable ending point at one end of its travel, of means settable to vary the other end of said travel, a driving member having a uniform movement, a scale for said carriage, and means settable at said scale for varying the said other end of said travel. 140
- 100 35. The combination with a gear wheel adapted to be turned, of a pinion adapted to run idly thereon, a handle for moving said pinion so that it will so run idly, a second pinion also adapted to run idly on said gear, a scale, a support for said second pinion adapted to be positioned according to said scale as the pinion runs idly, and a spring adapted to return said support to its normal position as determined by said scale. 145
- 105 36. The combination with a member hav- 150

ing a uniform stroke, of a belt adapted to return another member to a predetermined position, a scale for determining said position, a gear wheel connected to draw on said belt, a pinion adapted to run idly on said gear and connect it to said uniform stroke member, a second pinion adapted to run idly on said gear, a device upon which said second pinion is carried, and means for setting said device at a position determined by said scale.

37. The combination with a gear adapted to be turned variable amounts, of a member for turning it having a uniform stroke, a pinion connected to said member adapted to run idly on said gear, a second pinion adapted to run idly on said gear to mesh with the first pinion and lock it to said gear, a device upon which said second pinion is carried, a scale for positioning said device, a belt connecting said scale to said device, and a spring tensioning said belt.

38. The combination with a typewriter carriage, of a carriage-return mechanism having a movement always sufficient to return the carriage the full distance, an adjustable stop for limiting the travel of the carriage, and means controlled by said stop for determining whether the carriage-return mechanism shall operate to return the carriage the entire distance or any intermediate distance according to the setting of said stop.

39. The combination with a carriage, of a stop for limiting the travel of said carriage, an operator having a constant movement co-extensive with the full carriage traverse, a control for governing the extent of movement of said carriage by said operator, and connections between said stop and said control, whereby the action of the latter is governed from the former to an extent depending upon the adjustment of said stop.

40. The combination with a carriage, of a scale arranged in juxtaposition to said carriage, a margin-regulating device mounted

to move along said scale to determine the extent of travel of said carriage, an operator having a constant movement for traversing said carriage, and connections between said margin-regulating device and said operator for controlling the effective movement of the latter according to the position of said stop.

41. The combination with a carriage, of an operator having a constant movement for traversing said carriage, mechanism for effectively connecting said operator to said carriage for a certain portion of movement of said operator, a stop for limiting the movement of said carriage, and connections between said stop and said mechanism, whereby the duration of effective connection between said operator and said carriage is controlled from said stop.

42. The combination with a typewriter carriage, of an operator having a constant movement for traversing said carriage, said movement being co-extensive with the full traverse of said carriage, means to enable the constant movement of said operator to produce a variable movement of said carriage, and means for indicating the extent of movement of said carriage which will be produced at any certain time by said operator.

43. The combination with a traveling carriage, of an operator having a part moved a constant stroke for controlling the return of the carriage, a member variably adjustable to be encountered by said constant stroke part at different points in its movement, means controlled jointly by said constant stroke part and said adjustable member for returning the carriage, a stop for the carriage, and means controlled by said stop for variably adjusting said member.

FREDERICK A. HART.
